Primary Examiner — Marcus Jackson*(74) Attorney, Agent, or Firm* — Finnegan, Henderson, Farabow, Garrett & Dunner LLP(57) **CLAIM**

The ornamental design for a fog light, as shown and described.

DESCRIPTION

FIG. 1 is a front left perspective view of the truck including a fog light assembly;

FIG. 2 is a front left perspective view of the fog light assembly of the left fog light in FIG. 1, the front right perspective view of the fog light assembly of the right fog light being a mirror image thereof;

FIG. 3 is a right side view of the right fog light assembly in FIG. 1, the left side view of the left fog light assembly being a mirror image thereof;

FIG. 4 is a left side view of the right fog light assembly in FIG. 1, the right side view of the left fog light assembly being a mirror image thereof;

FIG. 5 is a top plan view of the right fog light assembly in FIG. 1, the top plan view of the left fog light assembly being a mirror image thereof;

FIG. 6 is a front view of the left fog light assembly in FIG. 1, the front view of the right fog light assembly being a mirror image thereof; and,

FIG. 7 is a back view of the right fog light assembly in FIG. 1, the back view of the left fog light assembly being a mirror image thereof.

The broken lines depict environmental structure and elements depicted in broken lines are not part of the claimed design.

1 Claim, 7 Drawing Sheets(56)
